(57) **CLAIM**

The ornamental design for a modular display rack with shelves, as shown and described.

DESCRIPTION

FIG. 1 is a front perspective view of a first embodiment of a modular display rack with shelves;

FIG. 2 is a top plan view of the modular display rack with shelves of FIG. 1;

FIG. 3 is a left-side view of the modular display rack with shelves of FIG. 1;

FIG. 4 is a front view of the modular display rack with shelves of FIG. 1;

FIG. 5 is a right-side view of the modular display rack with shelves of FIG. 1;

FIG. 6 is a rear view of the modular display rack with shelves of FIG. 1;

FIG. 7 is a bottom plan view of the modular display rack with shelves of FIG. 1.

FIG. 8 is a front perspective view of a second embodiment of a modular display rack with shelves, wherein the top module portion is dimensionally larger than in the embodiment of FIG. 1;

FIG. 9 is a top plan view of the modular display rack with shelves of FIG. 8;

FIG. 10 is a left-side view of the modular display rack with shelves of FIG. 8;

FIG. 11 is a front view of the modular display rack with shelves of FIG. 8;

FIG. 12 is a right-side view of the modular display rack with shelves of FIG. 8;

FIG. 13 is a rear view of the modular display rack with shelves of FIG. 8; and

FIG. 14 is a bottom plan view of the modular display rack with shelves of FIG. 8;

FIG. 15 is a front perspective view of a third embodiment of a modular display rack with shelves;

FIG. 16 is a top plan view of the modular display rack with shelves of FIG. 15;

FIG. 17 is a left-side view of the modular display rack with shelves of FIG. 15;

FIG. 18 is a front view of the modular display rack with shelves of FIG. 15;

FIG. 19 is a right-side view of the modular display rack with shelves of FIG. 15;

FIG. 20 is a rear view of the modular display rack with shelves of FIG. 15;

FIG. 21 is a bottom plan view of the modular display rack with shelves of FIG. 15;

FIG. 22 is a front perspective view of a fourth embodiment of a modular display rack with shelves, wherein the modular portion near the top of the rack is dimensionally larger than in the embodiment of FIG. 15;

FIG. 23 is a top plan view of the modular display rack with shelves of FIG. 22;

FIG. 24 is a left-side view of the modular display rack with shelves of FIG. 22;

FIG. 25 is a front view of the modular display rack with shelves of FIG. 22;

(Continued)

FIG. 26 is a right-side view of the modular display rack with shelves of FIG. 22;

FIG. 27 is a rear view of the modular display rack with shelves of FIG. 22; and,

FIG. 28 is a bottom plan view of the modular display rack with shelves of FIG. 22.
